CLAIM

The ornamental design for a pipefitter's magnetic tip for a measuring tape, as shown and described.

DESCRIPTION

FIG. 1 is a right side perspective view of the pipefitter's magnetic tip for a measuring tape embodying my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.
